DOP OR HOLDER FOR DIAMONDS AND LIKE
TOOL PIECES FOR GRINDING OR POLISH-
ING PURPOSES

Frederick Charles Jearum, Sutton, England

Application November 17, 1943, Serial No. 510,679
In Great Britain November 19, 1942

4 Claims. (Cl. 51—229)

This invention relates to dops or holders for diamond or other precious stone tool pieces or other tool pieces or tips of hard metal for grinding or polishing purposes in generating or shaping the diamond or other tool piece or tip, of the kind known as mechanical dops or holders, in contradistinction to those wherein the tool piece or tip is secured by cement or solder.

The aim of the present invention is to provide a mechanical dop or holder (for diamonds or other minerals or hard metals, hereinafter referred to as "stones") in which the holding or securing means can be readily adapted to conform to any particular shape or angle (such as the wedge angle of stones of wedge shape in plan) of the various shapes or angles possessed by stones to be operated upon without having to resort to machining or other accurate method of shaping the seating for the stone position.

The invention consists in a dop or holder of the character described comprising: a base member having at the forward end a flat bed for receiving and presenting the stone for grinding, polishing or the like to a lapping disc and having a longitudinal channel in rear of said bed, a backing device consisting of three or more parallel strips relatively slidable longitudinally in said channel to position their forward ends for engagement with the rearward shape of the stone as viewed in plan to locate it laterally and longitudinally on said bed, means operating laterally on said backing strips for clamping them in any adjusted position on said base member and a clamping member adapted to bear upon the upper side of the stone to secure it upon said bed.

The invention also consists in a dop or holder as set forth in the preceding paragraph wherein the backing strip device comprising a set of three strips has the ends of its outer strips shaped to engage the rearward facets of the stone, the end of the middle strip being engageable with the rearward extremity of the stone.

The invention further consists in a dop or holder wherein the backing device comprises a group of more than three strips having rounded forward ends and being sufficient in number such that the rounded ends define the outline of the rear adjacent part of the stone making a series of closely spaced contacts therewith when such strips are advanced along said channel for locating the stone laterally and longitudinally on said bed.

Further features of the invention will be hereinafter described and defined in the claims.

In the accompanying drawing which illustrates

several examples of modes of carrying the invention into effect,

Figure 1 is a side elevation of a dop according to the invention.

5 Figure 2 is a plan view according to Figure 1 with the cover plate and clamping member for the upper side of the stone removed.

Figure 3 is a plan view of one form of backing device strips assembled together side by side 10 for employment in any of the forms of dop described in the specification.

Figure 4 is a side elevation of a modified form of dop or holder.

Figure 5 is a longitudinal sectional view of the 15 dop shown in Figure 4, while

Figure 6 is a plan view thereof with the cover plate removed.

Figures 7 and 8 are respectively a plan and 20 elevation of a cover plate and conical locking plug described in reference to the form of the invention shown in Figure 4.

Figure 9 is a plan view of a modified form of dop while

Figure 10 is a plan view of a modified form 25 of base member for a dop according to the invention.

Figure 11 is a front end view of the base member seen in Figure 10, and

Figure 12 is a perspective view of a wedge or 30 chisel-shaped form of stone.

In carrying the invention into effect according to one form as described by way of example (see Figures 1 and 2) a base member 1 is provided with a flat bed or support 1a for the stone. This

35 bed or support may be a plain surfaces parallel with the bottom plane of the base (as seen in Figure 1) or at an angle thereto. On each side the base is provided with a longitudinal flange 1b to afford a parallel-walled channel in rear 40 of the position at which the stone is received upon the bed. A cover plate 2 is provided for the channel and is secured by set screws 2a, the bed 1a, the side flanges 1b and the cover plate 2 thus forming a tunnel for the reception of a

45 backing device generally designated 3' adapted to slide longitudinally within the tunnel. One of the flanges 1b and the corresponding side of the base is provided with a recess to receive a clamping jaw or foot 3 which is carried on a set screw or a bolt device such as 3a so as to bring pressure to bear upon the sides of the backing device to lock or clamp such in position after adjustment. The forward part of the base (in plan) is angular or bevelled to afford an appropriate grinding clearance and in elevation at the

50 55

forward end the base is undercut again for the purpose of providing a suitable grinding clearance.

A bridge piece 2b is provided upon the cover plate in which a set screw 2c is mounted for bearing upon a finger or clamping lever 4 the rear end of which is pivotally mounted between a pair of lugs 2d mounted at the rear of the cover plate. The lever 4 at the underside of its forward end is provided with a foot 5 having a series of upward projections which are bent over to form a cup or cage 5a for the rear of a ball 5b carried on a stem 5c which is located in the end of the clamping lever 4. This arrangement provides a clamping device which automatically adjusts itself to the inclination of the wedge shape (in vertical sectional elevation) or other form of the stone under treatment.

The backing device may comprise three parallel strips of metal a, b and c (see Figure 3) the front ends of the outer ones a and b of which are inwardly bevelled to an angle roughly corresponding with that of the mean angles of the wedges of stones likely to be met with. The middle strip c may have a square or concave end and is adapted to engage the extremity of the stone or be set back to accommodate its pointed end. Strips such as c may be provided in several widths for use with the outer strips a and b according to the rear face of the shank or back of the stone. Alternatively the side pieces a and b may have convex surfaces as viewed in plan the chord of which roughly corresponds with the mean angle of the wedge shapes it is adapted to accommodate. The convex form will, it will be appreciated, provide a line contact for a considerable variety of angles of wedge. In Figure 3 the three strips a, b and c are seen fitted together for insertion upon the bed 1a and beneath the cover plate 2 in place of the arrangement shown in Figure 1.

In setting up, a stone is positioned to protrude over the forward end of the base in the usual manner. The side strips of the backing device are then pushed forward in the tunnel until they engage the facets of the wedge of the rear of the stone. The centre strip is then pushed forward to act as an abutment for the rear extremity of the stone. When the stone has thus been laterally and longitudinally located in position, the side clamping jaw is screwed tight to prevent the backing device from moving and the finger described above is then positioned with its rounded tip upon the top surface of the stone and the set screw screwed down to clamp the stone firmly upon the bed. It will be observed that the side pieces, which need not fit the stone with absolute accuracy, may be readily filed, if necessary, to engage the shape of any particular stone to be ground.

The backing device 3', Fig. 2, may be said to comprise a group (for example seven or eight) of thin strips of metal or wire pieces d of round or square cross section which are slideable in the channel between the flanges 1b and under the cover plate 2. The strips are preferably formed with rounded stone-engaging ends. In this form, when the stone has been seated and held in position by the clamping device, each of the backing strips or wires in turn is pushed forward to cause them individually to contact with the rear face of the stone so that when all the strips have been pushed forward the number employed is such that their ends correspond with or define the outline or profile of the rear adjacent part of the stone, making a series of closely spaced line

or point contacts therewith. When the rear strips have been adjusted they are clamped in position by the lateral jaw 3 as described above.

In carrying the invention into effect according to another mode (see Figures 4 to 8) the base member 1' is provided with a bed channel 1a' for receiving a backing device of the character already described and embodies a modified form of cover plate and means for locking or clamping the backing device in the adjusted position. The flanges 1b' of the base element are formed with undercut or dovetail longitudinal grooves and the cover plate 2' (Figure 7) has bevelled longitudinal edges so that the cover plate may be slid into position in the grooves. The cover plate has lugs 2b' in which is pivoted a stone clamping lever 4' having a downwardly turned front end finger and an abutment screw 2c' at the rear for bringing clamping pressure to bear upon the stone. Alternatively the lever may have a ball-jointed foot of the kind described in reference to Figure 1.

The channel bed 1a' and the adjacent side walls have a conical cavity or bore 6 into which a locking plug of conical shape 7 is adapted to fit. The plug 7 has a channel 7a cut across its upper surface to correspond with the channel 1a' so as to provide wings 7b for engaging the sides of the backing device and clamping such in adjusted positions. The plug has a vertical slit 7c or is slotted as at 7c to enable the wings 7a to approach one another to produce the clamping pressure.

The body of the conical plug has a tapered bore 7d for receiving the taper or wedge-shaped end of a locking spindle 8 which is screwthreaded at 8a at its outer end and terminates with a milled operating head 8b. The spindle 8 is adapted to enter the longitudinal bore 1c in the base member 1 and the screwthreaded portion 8a is adapted to engage the internal screwthread 1d. When the spindle is advanced forwardly through the bore 1c its tapered end which is normally out of coaxial alignment with the tapered bore 7d in the plug 7, pulls the latter downwardly in its conical cavity 6 and thus causes the wings 7a to approach one another and operate with a clamping action on the backing device. When the spindle is retracted the resilience afforded by the slotted form of the plug causes the clamping pressure of the wings 7b to be relieved.

The bed 1a' may be provided with a backing device in any of the single or multiple forms described above with reference to Figures 1 and 3.

In Figure 9 is illustrated a modified shape of base member 1'' fitted with a cover plate 2'' such as already described, a conical locking device 6' and operating spindle 8' as described above in reference to Figures 4 to 8. This form of the invention is adapted more particularly for cutting, grinding and polishing the flanks or shank walls of a stone and hence the front face of the member 1'' may be rectilinear. The backing device may comprise a series of strip members of the character such as shown in Figure 3 or it may comprise a considerable number of narrow strips d such as illustrated in Figure 2 which may be adjusted so that their forward ends outline the shape of the flanks or side surfaces and a part of the bevelled tip of the stone to be treated.

In Figures 10 and 11 are illustrated a modification of the bed 1''' for accommodating stones the base or under surface of which is of wedge or chisel shape such as seen in enlarged form in Figure 12. In this case the forward portion 5 of the bed 1''' is provided with a groove 1e of

V shape in cross section in which the wedge of a diamond (Figure 12) is seated. Also the flanges '1b''' are provided with dovetailed grooves for accommodating the bevelled edges of a cover plate. Otherwise the base member shown in Figures 10 and 11 may be of similar construction and is adapted to receive a cover plate and backing device locking means similar to those already described.

The forward portion or nose of the various base members described above may be bevelled (in plan) to a minimum angle suitable for the accommodation of stones of a range of angles or a series of base members may be made with different nose angles such as seen in Figures 2, 6 and 10, to suit the angles of the various stones to be treated.

The various base members described above may be secured upon a dop holding arm or feed or other support in any suitable manner, for example, the base members may have a screwthreaded cavity such as '1f' shown in Figure 1 adapted to be engaged by a set screw carried by the dop arm or support to attach the base members in position thereon.

It is to be understood that the several modifications described in reference to particular figures may be applied to the invention described in connection with other figures or forms.

I claim:

1. A dop or holder of the character described comprising: a base member having at the forward end a flat bed for receiving and presenting the stone for grinding, polishing or the like to a lapping disc and having a longitudinal channel in rear of said bed, a backing device consisting of three or more parallel strips relatively slidable longitudinally in said channel to position their

forward ends for engagement with the rearward shape of the stone as viewed in plan to locate it laterally and longitudinally on said bed, means operating laterally on said backing strips for

5 clamping them in any adjusted position on said base member, a cover removably mounted on the base member and overlying the channel to form a tunnel through which the backing strips are slideable and a clamping member adapted to bear upon the upper side of the stone to secure it upon said bed.

2. A dop or holder as claimed in claim 1, wherein clamping means for the backing strips comprise: a split conical plug having a through way aperture for receiving the conical end of a spindle and having wings forming a short channel for engaging the sides of the outer of the backing strips; a conical seating in the base channel for the plug and a longitudinally displaceable 15 screwthreaded spindle having a tapered end for entering the aperture in the plug and drawing it into its seating to clamp the wings laterally upon the strips.

3. A dop or holder as claimed in claim 1, 25 wherein the base member has at one side a recess and wherein the clamping means for the backing strips comprise: a bolt device having at one end a clamping jaw which is located in said recess in the base member for engaging the adjacent 30 backing strip and bringing lateral pressure to bear to clamp the strips in their adjusted position in the channel of the base member.

4. A dop or holder as claimed in claim 1, 35 wherein the clamping member for the upper side of the stone comprises a lever the forward end of which has a cup and ball foot for engaging said upper side of the stone.

FREDERICK CHARLES JEARUM.
